UNITED STATES PATENT OFFICE

151,632

DESIGN FOR A FLUORESCENT LIGHTING UNIT

George Gomberg, Chicago, Ill.

Application August 2, 1947, Serial No. 140,682

Term of patent 3½ years

(Cl. D48—23)

To all whom it may concern:

Be it known that I, George Gomberg, a citizen of the United States, residing at Chicago, in the county of Cook and State of Illinois, have invented a new, original, and ornamental Design for Fluorescent Lighting Unit, of which the following is a specification, reference being made to the accompanying drawing, forming a part thereof.

In the drawing:

Fig. 1 is an edge elevational view of fluorescent lighting unit, embodying my new design;

Fig. 2 is a bottom plan view thereof;

Fig. 3 is a top plan view of the same; and

Fig. 4 is a fragmentary vertical sectional view on line 4—4 of Fig. 2.

I claim:

The ornamental design for a fluorescent lighting unit, substantially as shown.

GEORGE GOMBERG.
